JOHN R. HAMILTON, OF YONKERS, NEW YORK, ASSIGNOR TO SYPHO-CHEMICAL SPRINKLER CORPORATION, OF CROTON-ON-HUDSON, NEW YORK, A CORPORATION OF NEW YORK.

AUTOMATIC FIRE-EXTINGUISHING APPARATUS.

1,313,292.

Specification of Letters Patent.

Patented Aug. 19, 1919.

Application filed August 6, 1915. Serial No. 43,912.

To all whom it may concern:

Be it known that I, JOHN R. HAMILTON, a citizen of the United States, and resident of Yonkers, county of Westchester, State of New York, have made a certain new and useful Invention Relating to Automatic Fire-Extinguishing Apparatus, of which the following is a specification, taken in connection with the accompanying drawing, 10 which forms part of the same.

This invention relates especially to chemical fire extinguishing apparatus in which a distributing system which may comprise automatic or other distributing devices arranged at suitable points around the building is connected to a supplemental supply of extinguishing liquid and is normally kept at substantially the desired emergency pressure. Under emergency conditions extinguishing liquid can be supplied to the distributing system preferably through chemical pressure producing means which may comprise a pressure responsive automatic discharging device for controlling the discharge of one of the pressure producing chemicals in such way as to maintain a substantially constant discharge pressure from the system throughout at least a large part of its emergency action. 20

In the accompanying drawing showing in a somewhat diagrammatic way illustrative embodiments of this invention—

Figure 1 is a sectional elevation showing one form of the invention.

Fig. 2 is a similar view showing a modification; and

Fig. 3 is a similar section showing still another form.

The distributing system may be of any desired form and construction and may, for instance, comprise a supply pipe 3 and suitable distributing lines, such as 6, connected therewith and provided with automatic or other distributing devices such as the automatic sprinkler head 7 arranged at suitable points around the building to be protected. In order to effect its more rapid and effective action under emergency conditions the 40 distributing system may in some cases be normally charged with extinguishing liquid of any suitable character, non-freezing solutions being desirable for low temperature work. A supplemental supply of extin-

guishing liquid of any suitable character 55 may be arranged in connection with the distributing system so as to be operated preferably by chemically produced pressure generated in any suitable way and supply additional extinguishing liquid to the system under emergency conditions. This supplemental supply may, for example, comprise a chemical pressure tank 1 containing a charge 5 of pressure producing extinguishing liquid, such as the ordinary carbonate 60 solution, and a suitable supply connection 2 and strainer 4 may be used to supply this liquid to the supply pipe 3 or other part of the distributing system under emergency 65 conditions.

For some purposes it is desirable to normally keep the distributing system under the desired emergency pressure of 50 to 100 pounds or so per square inch and this may be conveniently effected by maintaining a 70 corresponding air pressure in the upper part of the tank 1 through any suitable means or connections, and it is desirable in order to minimize air absorption to interpose a 75 film or layer of relatively non-absorptive material between the liquid in the tank and the air or other pressure medium employed above. For this purpose a thin layer or film 45 of relatively heavy mineral oil may 80 be used, for example, a few ounces being sufficient to prevent undesirable absorptive contact throughout a tank of considerable 85 size. The chemical mixing means for causing or maintaining the desired emergency 90 pressure may be of any suitable character whatever, preferably comprising a pressure responsive member or diaphragm which may act to constantly maintain the tank pressure 95 at the desired amount above that of the atmosphere. For this purpose a suitable casting or acid chamber 15 may be mounted on the tank to hold a charge 17 of sulfuric acid or other pressure producing chemical, a resilient diaphragm or member 9 being arranged, if desired, above the top of the chamber so as to be subjected through the large size equalizing passage 16 to the pressure within the tank which is thus also exerted on top of the chemical charge 17. 100 This pressure responsive diaphragm may, if desired, be directly connected to the automatic discharging means or valve 18 as

through the valve stem 8 and a spring such as 10 may coöperate with the diaphragm so as to exert thereon the desired pressure and cause the valve 18 to open when the tank pressure falls below the desired emergency pressure, of, say, 50 to 100 pounds above that of the atmosphere. If desired, a suitable adjusting screw 12 and lock nut 11 may be arranged to adjust the effective pressure exerted by this spring and may force the spring down to the desired extent through the action of the interposed washer 13 mounted within the yoke or frame 14 which may also serve to hold the diaphragm 9 in position tightly closing the top of the acid casing. Under emergency conditions when one or more of the distributing devices automatically open to discharge liquid from the system this causes a sufficient reduction in the tank pressure so that this pressure is no longer sufficient to hold the pressure responsive diaphragm in its upper position indicated and the spring can thus force it downward, thus slightly opening the automatically discharging valve 18 and allowing acid to descend into the mixing tank where it promptly develops further pressure through its chemical action on the carbonate extinguishing liquid charge 5. In this way sufficient chemical pressure is produced so that the tank pressure is restored to the desired emergency pressure which thereupon raises the diaphragm and connected discharging valve into the closed position indicated in Fig. 1. For some purposes it is desirable to have the valve open gradually so that its first movement discharges relatively small quantities of the pressure producing chemical while further opening movement discharges the chemical more and more rapidly. For this purpose it is sometimes desirable to have the valve formed with the slightly conical shape, the angle being somewhat exaggerated in Fig. 1; and this progressively opening action may also be promoted by making the valve seat 47 relatively thin where it coacts with the conical face of the valve and by forming if desired a flat or receding portion 48 slightly above this valve seat when the valve is closed, so that when any considerable opening movement occurs a relatively large discharge opening is produced through which much larger quantities are discharged than through the small annular opening around the conical valve when it first opens.

Another arrangement is shown in Fig. 2 as comprising a dry pipe distributing system connected to a similar supplemental supply of extinguishing liquid or mixing tank 1, a pin hole equalizing passage 32, the size of which is much exaggerated in the drawing, being preferably provided in the supply connection 2 somewhat above the normal level of the charge 5 of carbonate or other

extinguishing liquid in the tank which may normally be kept at the desired emergency pressure of 50 to 100 pounds a square inch more or less. The supplemental pressure producing means may in this case comprise 70 a casing 30 mounted on the tank and containing a chemical or acid chamber 29 having the charge 24 of sulfuric acid or other pressure producing chemical normally contained in its lower portion while its relatively larger upper portion can be maintained air-tight when the filling plug 31 is screwed home. The automatic discharging means comprises a suitable siphon in this case having a discharge leg 22 communicating through the apertures 25 with the bell shaped receiving leg or member 23 which may be arranged around the same so that when the top of the siphon is closed the acid charge may enter at the point 28 and be 80 freely discharged through suitable openings, such as 21, at the bottom of the discharge leg so as to mix with the carbonate liquid 5. Such action naturally occurs under emergency conditions when the discharge of liquid 90 from the system lowers the air or other gaseous pressure in the top of the tank so that it is then less than the pressure of the air above the acid charge, thus causing the discharge of acid until sufficient additional 95 pressure is chemically developed in the tank to stop this action. It is for some purposes desirable to have the air space of the acid chamber normally in communication with the air space in the main tank and this may 100 be conveniently effected by forming an equalizing venting passage 26 in the upper part of the siphon device so that the automatically closing vent valve 27 may tightly close this passage under emergency conditions when the float 19 connected to this valve through the stem 20 falls on the first substantial discharge of liquid from the tank. In this way no undesirable action 105 may be caused by ordinary temperature variations and yet as soon as any one of the distributing devices comes into emergency action the float and connected vent valve descend and the further intermittent feeding 110 of the pressure producing acid charge continues whenever the tank pressure drops until practically the entire charge of acid has been discharged into the mixing tank.

Another arrangement is shown in Fig. 3 as comprising a wet pipe distributing system which may be normally charged with any suitable extinguishing liquid 33, such as suitable non-freezing solution for instance, above the check valve 35. The system may be kept under the desired emergency pressure by maintaining this pressure in the upper part of the mixing tank above the charge of carbonate or other extinguishing liquid 5 therein and if desired a suitable priming pressure chamber 36 may be 115 120 125 130

used in connection with the distributing system and connected thereto as through the priming connection 34 between the system and the lower part of this priming tank, the 5 upper part of which may be connected through an air connection or pipe 37 with the air space in the chemical tank. Under emergency conditions the discharge of liquid from one or more of the sprinkler heads 10 or other distributing devices causes the discharge of liquid from the system and the consequent reduction in the pressure of the air or other gaseous medium in the top of the tank so as to bring into action the pressure 15 responsive chemical mixing devices shown which may be of substantially the same construction and arrangement as described in connection with Fig. 1. In this way the sulfuric acid or other pressure producing 20 chemical 17 is gradually discharged from the acid chamber in amounts sufficient to substantially maintain the emergency pressure in the tank and system throughout at least a considerable part of the discharge of the 25 liquid in the tank.

This invention has been described in connection with a number of illustrative embodiments, forms, arrangements, materials, proportions, sizes and parts of the apparatus, to the details of which disclosure the invention is not of course to be limited, since what is claimed as new and what is desired to be secured by Letters Patent is set forth in the appended claims:

35 1. In automatic chemical fire extinguishing apparatus, a distributing system normally charged with carbonate extinguishing liquid and comprising automatic distributing devices, a connected supplemental supply 40 of extinguishing liquid comprising a chemical mixing tank charged with carbonate extinguishing liquid and normally kept under the desired emergency pneumatic pressure and coöperating chemical mixing devices, 45 comprising an acid chamber provided with pressure responsive automatic discharging means comprising a valve allowing progressively increasing rates of discharge as it opens and a directly connected pressure responsive 50 resilient diaphragm above said acid charge and acted on on one side by the pressure within said mixing tank and acted on on the other side by atmospheric pressure and an adjustable compensating spring 55 tending to open said valve on substantial decrease of the pressure in said tank in order to compensate for any gradual pressure reduction during the inoperative condition of the system and to substantially maintain 60 such emergency pressure during fire emergency conditions.

2. In automatic chemical fire extinguishing apparatus, a distributing system comprising automatic distributing devices, a 65 connected supplemental supply of extin-

guishing liquid comprising a chemical mixing tank charged with carbonic extinguishing liquid and normally kept under the desired emergency pneumatic pressure and coöperating chemical mixing devices comprising 70 an acid chamber provided with pressure responsive automatic discharging means comprising a valve allowing progressively increasing rates of discharge as it opens and a directly connected pressure responsive 75 diaphragm above said acid charge and acted on on one side by the pressure within said mixing tank and acted on on the other side by atmospheric pressure and a compensating spring tending to open said valve on 80 substantial decrease of the pressure in said tank in order to compensate for any gradual pressure reduction during the inoperative condition of the system and to substantially maintain such emergency pressure during 85 fire emergency conditions.

3. In automatic chemical fire extinguishing apparatus, a distributing system comprising distributing devices, a connected supplemental supply 90 of extinguishing liquid comprising a chemical mixing tank charged with carbonate liquid and normally kept under the desired emergency pneumatic pressure and coöperating chemical mixing devices comprising an acid chamber provided with pressure responsive automatic discharging means comprising a valve and a connected pressure responsive diaphragm 95 above said acid charge and acted on on one side by the pressure within said mixing 100 tank tending to open said valve on substantial decrease of the pressure in said tank in order to compensate for any gradual pressure reduction during the inoperative condition of the system and to substantially maintain such emergency pressure during fire 105 emergency conditions.

4. In chemical fire extinguishing apparatus, a distributing system normally charged with extinguishing liquid and comprising automatic distributing devices, a connected supplemental supply of extinguishing liquid comprising a chemical mixing tank charged with carbonate extinguishing liquid and normally kept under the desired emergency pressure and coöperating chemical mixing devices comprising an acid chamber provided with pressure responsive automatic discharging means comprising a valve allowing progressively increasing rates of discharge as it opens and a connected pressure responsive diaphragm above said acid charge and acted on on one side by the pressure within said mixing tank and acted on on the other side by atmospheric pressure and tending to open on substantial decrease of the pressure in said tank.

5. In fire extinguishing apparatus, a distributing system normally charged with extinguishing liquid and comprising distribut-

- ng devices, a connected supplemental supply of extinguishing liquid comprising a chemical mixing tank charged with carbonate extinguishing liquid and normally kept under
5 the desired emergency pressure and coöperating chemical mixing devices comprising an acid chamber provided with pressure responsive automatic discharging means comprising a valve and a connected pressure responsive diaphragm acted on on one
10

side by the pressure within said mixing tank and acted on on the other side by atmospheric pressure and tending to open on substantial decrease of the pressure in said tank.
